PACKAGE TIE

Filed Feb. 14, 1930

Inventor
John J. Lynch

By Donald L. Maxson
Attorney

UNITED STATES PATENT OFFICE

JOHN J. LYNCH, OF RIVERDALE, MARYLAND

PACKAGE TIE

Application filed February 14, 1930. Serial No. 428,312.

My invention relates to improvements in package and article ties, and more particularly to a specific system or method of tying a package or article, whereby a single piece or 5 length of cord will be so disposed about the package that each of the four corners of the package will have a section of the cord overlying and underlying the same, the sides of the package will be protected by the crossing 10 of the cord, and an adjustable draw knot will be provided at one end of the package, said crossing of the cord at the sides of the package providing a ready and convenient finger grip whereby the package may safely be carried. 15

An object of the invention is to provide an improved package or article tie utilizing a single length of cord and without any mechanical element attached to the cord, where- 20 by a package or article may be securely fastened at each of its corners, and at each side thereof, and the further provision of a drawing loop and an adjustable knot for positively and automatically tensioning the cord the de- 25 sired amount about the package being tied.

Another object of the invention is to pro- 30 vide an improved package tie which when tied about a package will be so arranged that the cord will be spaced in substantially par- allel relation to overlie and underlie the se- 35 veral corners of the package, thereby protect- ing the corners in handling or shipment of the package.

A further object of the invention is to pro- 35 vide an improved package or article tie, which will utilize a single length of cord, and which will be partially arranged about the package, and after twisting the package, the balance of the tie will be placed on the package, thereby 40 providing an efficient and novel form of tie.

Other objects will appear as the description proceeds.

In the accompanying drawings which con- 45 stitute a part of my application,

Figure 1 is a perspective view of a pack- age with my improved wrapping system or package tie incorporated thereon;

Figure 2 is a perspective view of my im- 50 proved package tie, showing a package in dotted lines within the tie, and

Figure 3 is a fragmentary detail view of the draw loop and adjustable tying knot used in securing my package tie in position.

Like characters of reference are used throughout the following specification and the accompanying drawings to designate cor- 55 responding parts.

In carrying out my invention, I provide a single length of cord 1 which will have its opposite ends designated 2 and 3. 60

In tying the package or article 4, I take the end 2 of the cord 1, and begin at the end of the package and at the top thereof, and place the cord over the adjacent corner of the package, down the side thereof and under the next adjacent corner of the package, then up the far end of the package and across the top of the package diametrically opposite the starting corner, then down the adjacent side, and under the corner of the right hand end of the package as illustrated in Figures 1 and 2, whereupon the cord is then twisted with the end 2 by turning the pack- age over, and the cord placed under the nearest corner of the package, as illustrated, 70 up the adjacent side thereof, over the next corner, down over the far end of the package and under the corner diametrically opposite the corner from which the start was made, up the adjacent side of the box, and across 75 the top of the corner of the box or pack- age at the right hand end of the same as illustrated in Figures 1 and 2, and is then placed under the starting point, as shown in Figure 3, drawn taught, and a second loop 80 taken and the knot drawn tight.

To make it more clear as to the specific manner in which the tie is placed on a pack- age, I have designated the starting point as 85 *a*, and have placed arrows on the drawings to show the direction and progress of the cord as applied, and the finishing point is designated at *b*.

It will be understood that when packages are tied merely in the customary cross-wise 90 manner, the corners are unprotected and often the cord is slipped from the package, or the lid of a box torn loose, but with the method or system I employ, the corners 95 are absolutely protected, and the crossed 100

cord at the sides or ends of the package afford an excellent finger grip for carrying the package.

Minor changes may be resorted to without 5 departure from the spirit of the invention.

Having thus described my invention what I claim as new and desire to secure by Letters Patent of the United States is:

1. The system of forming a package tie 10 comprising the passing of a single length of cord alternately over and under the adjacent corners of the package, forming a twist in the cord by turning the package, and again alternately passing the cord under and over 15 adjacent corners of the package.

2. The subject matter of claim 1, and engaging the starting length of the cord by the free end thereof, drawing the same taught, and securely knotting the same.

20 3. The subject matter of claim 1, engaging the starting length of the cord by looping the free end thereof through the same, tensioning the twisted portion of the cord, and forming a securing knot over the looped 25 portion of the cord.

In testimony whereof I affix my signature.

JOHN J. LYNCH.
